R. A. Parsons.
Guide for Gang Saw.
N° 92,990. Patented Jul. 27, 1869.

O. D. Kinman.

Inventor;

Richard A. Parsons

United States Patent Office.

RICHARD A. PARSONS, OF CLINTON, IOWA, ASSIGNOR TO HIMSELF
AND TEN BROCK & NOYES, OF SAME PLACE.

Letters Patent No. 92,996, dated July 27, 1869.

IMPROVEMENT IN GUIDES FOR GANG-SAW GATES.

The Schedule referred to in these Letters Patent and making part of the same.

To all whom it may concern:

Be it known that I, RICHARD A. PARSONS, of the city of Clinton, in the county of Clinton, in the State of Iowa, have invented a new and useful Improvement in Guides for Gang-Saw Gates; and I do hereby declare that the following is a full and exact description of the same, reference being had to the accompanying drawings, and to the letters of reference marked thereon.

The nature of my invention consists in so constructing and arranging the back and front guides on a saw-gate, that as the constant wear lets the gate work loose, the face or front guides may be quickly, uniformly, and securely tightened against the saw-gate, and adjusting it correctly, without having to fit in thin pieces, that are a constant annoyance.

To enable others to fully understand my invention, that they may construct and use it, I will describe its construction and operation.

First, I will explain the drawing, and then more minutely describe it in detail.

Figure 1 is a perspective view, showing all the parts necessary to explain my invention.

A A represent the fender-posts, to be cast-iron.

B B B represent inclined cast-iron pieces, fitted on to the fender-posts A A.

C C C represent the front or face-guide.

D D represent the back or V-guide.

E E E represent oil-cup, or a hole in top end of guides, to put oil, for lubricating the guides.

F represents the saws.

G G represent the cross-bars to saw-gate.

H H represent the stiles or side to saw-gate.

J J J represent pieces bolted to gate, to wear against the guides.

K K K K represent adjusting-rod, fitted with tightening-nuts.

P P P P P P P P P P represent arm-pieces, cast on the front guide-pieces C C C C, and are fitted to the incline-pieces B B B, as shown.

R R represent a stay-piece on fender-posts, to secure the adjusting-rod K K K K to.

I construct the fender-posts of cast-iron, having a square plane surface on the face, to receive the incline pieces B B B B.

These inclines are constructed with a slot through

them, to allow the bolt to pass through that confines the front guide C, by the arm-pieces P P P, to its place.

The back or V-guides are secured to their places by stays bolted to or cast on fender-posts.

All the guides are constructed with a receptacle for oil. A small opening from the oil-chamber to the wearing-surface of the guides allows the oil to pass out and oil the necessary parts.

After being used for some time, the wearing-parts, from the constant friction on them, become worn away, and the gate is too loose, and it becomes necessary to "tighten" the guides. To do this, loosen the bolts that confine the front guides C C C C, which pass through the arm-pieces P P, &c., into the fender-post. Then adjust the nuts on the rods K K K K, so as to draw the incline pieces B B, at bottom of gate, up toward the centre, and the inclines B B, at top of gate, down toward the centre, the slots in these pieces allowing them to move, while the bolt remains in its place.

It will be seen, that by moving the inclines as above, that the face-guides will close down to the gate as much as the angle of the incline differs from the seat of these pieces on the fender-posts, and, by means of the rods K K K K, and their adjusting-nuts, on the stay-piece R, the exact amount of tightening necessary may be quickly done. After having moved the inclines the required distance, tighten up the bolts that confine the arm-pieces P P P P P P P P P P, and, by them, the face-guides C C C C, and the object is accomplished, without having to adjust with small "bits" of leather, tin, or something else, as in the ordinary way.

What I claim as my invention, and desire to secure by Letters Patent, is—

The combination and arrangement of the fender-posts A A, the adjustable inclined pieces B B B B, the arms P P P P P P P P P P, supporting and fixing the guide-bars C C C C, when constructed and arranged substantially as and for the purpose herein set forth.

RICHARD A. PARSONS.
